UNITED STATES PATENT OFFICE.

EUGENE H. H. SMITH, OF NEW YORK, N. Y., AND IRVING V. SMITH, OF GLASTONBURY, CONNECTICUT.

DESIGN FOR A SPOON OR SIMILAR ARTICLE.

Application filed August 23, 1920. Serial No. 405,528. Term of patent 3½ years.

To all whom it may concern:

Be it known that we, EUGENE H. H. SMITH, a citizen of the United States, and a resident of New York, in the county and State of New York, and IRVING V. SMITH, a citizen of the United States, and a resident of Glastonbury, in the county of Hartford and State of Connecticut, have jointly invented a new, original, and ornamental Design for a Spoon or Similar Article, of which the following is a specification, reference being had to the accompanying drawing, forming a part thereof.

Fig. 1 is a plan view of the obverse of the handle for a spoon, fork, or similar article, showing our new design.

Fig. 2 is a plan view of the reverse.

Fig. 3 is a sectional view taken on the line 3—3 of Fig. 1 looking in the direction of the arrows.

Fig. 4 is a cross section taken on the line 4—4 of Fig. 1 looking in the direction of the arrows.

We claim:

The ornamental design for a spoon, or similar article as shown.

EUGENE H. H. SMITH.
